(57) **CLAIM**

The ornamental design for a pair of burner grates for a cooking appliance, as shown and described.

DESCRIPTION

FIG. 1 is a front perspective view of a pair of burner grates for a cooking appliance according to the design in a condition of use;

FIG. 2 is a front perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a right side elevation view thereof; and,

FIG. 8 is a left side elevation view thereof.

The portions of the article shown in evenly spaced broken line form no part of the claimed design.

Dash-dot broken lines adjacent un-shaded areas represent bounds of the claimed design and form no part of the claimed design themselves.

1 Claim, 6 Drawing Sheets
